BIB WITH CATCH-POCKET

Karl Gösta Berill Andersson, Halmstad, Sweden,
assignor to Duni Bila AB, Halmstad, Sweden

Filed Apr. 16, 1973, Ser. No. 351,189

Term of patent 14 years

Int. Cl. D2—02

U.S. Cl. D2—229

FIG. 1.

FIG. 3.

FIG. 2.

FIG. 1 is a front perspective view of a bib showing my new design in a flat position;

FIG. 2 is a front perspective view thereof in a wearing position; and

FIG. 3 is a rear perspective view of the bib in a flat position.

I claim:

The ornamental design for a bib with catch-pocket, as shown and described.
